UNITED STATES PATENT OFFICE.

GEORGE RIESECK, OF ALLEGHENY, PENNSYLVANIA.

SHAFT-SUPPORT.

SPECIFICATION forming part of Letters Patent No. 408,680, dated August 6, 1889.

Application filed March 18, 1889. Serial No. 303,808. (No model.)

To all whom it may concern:

Be it known that I, GEORGE RIESECK, a citizen of the United States, residing at Allegheny, in the county of Allegheny, State of Pennsylvania, have invented certain new and useful Improvements in Shaft-Supports; and I do hereby declare the following to be a full, clear, and exact description of the invention, such as will enable others skilled in the art to which it pertains to make and use the same, reference being had to the accompanying drawings.

My invention relates to an improvement in journal-bearings; and it consists in a means whereby the shaft contained in the said bearing may be adjusted, regardless of the position of the bearing, together with certain other details of construction and combination of parts, as will be fully set forth hereinafter.

In the accompanying drawings, Figure 1 is a side elevation of my improved journal-bearing, shown in connection with an ordinary shaft hanger or bracket. Fig. 2 is a side central sectional elevation of the same. Fig. 3 is a detailed side view of the lugs formed on the hanger. Fig. 4 is a plan view of the drip-pan. Fig. 5 is a side elevation of the same. Figs. 6, 7, and 8 are views of a modification in which the drip-pan has been omitted. Figs. 9 and 10 show my improvement connected with a pillow-block. Figs. 11 and 12 show another modification adapted to a pillow-block.

To put my invention into practice with an ordinary overhead hanger or bracket 1, I form on each inner side of the same two lugs or projections 7 8, the one 8 above the other 7, and between which the drip-pan 2, having 40 semicircular hollow lugs 6, is secured. This drip-pan 2, when in position, is capable of a short rotary movement, and is prevented from being elevated vertically by the upper lugs 8. At the base of this pan 2 and integral therewith is an upwardly-extending boss 3, which supports the shaft-bearing 5.

The said bearing 5 is provided with a short stem 4, which enters the boss 3, and is confined therein by a set-screw 9.

In operation the bracket or hanger 1 is secured in position without any accurate ad-

justment, except in the direction of the length of the shaft 10. The drip-pan 2 is placed in position by first entering one end of the hollow lugs 6 between the projections 7 8 and 55 the short stem 4, secured in the boss 3. By this construction it will be seen that the shaft 10 may be adjusted either in a horizontal or vertical direction. The short stem 4 may be raised in its socket and revolved to conform 60 with the shaft 10, and secured in the desired position by the set-screw 9, while the shaft 10 may be adjusted vertically by elevating or lowering the stem 4 in its socket, and the bearing 5 adjust itself to the shaft 10 by the 65 oscillation of the drip-pan.

At Figs. 6, 7, and 8 on the drawings I have shown a modification of my improvement, in which the drip-pan 2 is dispensed with and the hollow lugs 6 cast or formed on the bearing 70 5. This will permit the shaft 10 to adjust itself in but one direction, as the bearing may rock or move on the lugs 6.

At Figs. 9 and 10 the same construction last described is shown in connection with 75 the frame 12 of a pillow-block. At Figs. 11 and 12 I have shown the same bearing connected to a pillow-block, as shown at Fig. 1 on the drawings.

Having thus described my invention, what I 80 claim, and desire to secure by Letters Patent, is—

1. In combination with a shaft-support such as described, the frame having formed thereon the lugs or projections 7 8, and the drip-pan 85 2, provided with the hollow lugs 6, adapted to engage with the projections 7 8, whereby the said drip-pan may oscillate in its bearings, as and for the purpose set forth.

2. In a shaft-support, the combination of 90 the frame 1, provided with the two sets of lugs 7 8, the drip-pan 2, having formed thereon two hollow lugs 6, adapted to engage with the said projections 7 8, the socket 3, and pivoted bearing 5, having stem 4, and the set-screw 9, 95 for adjusting the said bearing 5, substantially as set forth.

3. In a shaft-support such as described, the drip-pan 2, detachably pivoted to the frame 1, provided with the socket 3, formed integral 100 therewith, the bearing 5, having stem 4, pivoted in the said socket 3, and a set-screw 9, for

adjusting the bearing 5, whereby the said bearing 5 may be adjusted vertically and horizontally.

4. In a shaft-support, the frame having 5 formed integral therewith the projections 7 8, and the bearing provided with two semicircular lugs 6, adapted to engage with the projections 7 8 on the frame to confine the bearing in position and permit the same to adjust itself to the shaft 10.

In testimony that I claim the foregoing I hereunto affix my signature this 15th day of March, A. D. 1889.

GEORGE RIESECK. [L. s.]

In presence of—

CHAS. RIESECK,
GEORG SOEHER.
